UNITED STATES PATENT OFFICE.

JOHN J. FRANK, OF SCHENECTADY, NEW YORK, ASSIGNOR TO GENERAL ELECTRIC COMPANY, A CORPORATION OF NEW YORK.

TRANSFORMER.

No. 853,778.

Specification of Letters Patent.

Patented May 14, 1907.

Application filed September 10, 1906. Serial No. 333,915.

To all whom it may concern:

Be it known that I, JOHN J. FRANK, a citizen of the United States, residing at Schenectady, county of Schenectady, State of New York, have invented certain new and useful Improvements in Transformers, of which the following is a specification.

My invention relates to transformers provided with regulating leads for varying the number of turns of one or both windings. It has been customary heretofore to connect such regulating leads to points on a winding near its terminals. The introduction of these leads necessarily somewhat weakens the insulation, and it has been found in practice that burn-outs have most frequently occurred at the points on the windings where the leads are connected.

My invention consists in connecting the regulating leads to points near the center of the winding, so that portions of the winding at or near its center are cut out in regulating the number of turns. Since the central portion of the winding is ordinarily somewhere near earth potential, the insulation of this portion of the winding is subjected to a small strain, so that the weakening of the insulation at this point by the introduction of the regulating leads becomes a matter of small importance.

My invention will be best understood from the accompanying drawing which shows a transformer provided with regulating leads arranged in accordance with my invention.

I have illustrated my invention as applied to the type of transformer described in Patent No. 687,048, issued to W. S. Moody, Nov. 19th, 1901, in which the winding is composed of independent coils mounted on opposite sides of a rectangular core and connected in series.

My invention is particularly advantageous when applied to this type of transformer, but it will be understood that in its broader aspects it is not limited to this particular type.

In the drawing, A represents a magnetic rectangular core on opposite sides of which are mounted the primary and secondary coils B and C. The upper coils are connect-

ed in the usual manner to the primary and 50 secondary terminals b and c, respectively.

b' b' represents regulating leads brought out from the two lower primary coils. Any two of these leads may be connected in any suitable manner as by the connecting member D, so as to place the two sets of coils on opposite sides of the core in series. By connecting different pairs of the leads b' together, portions of the primary winding formed by the coils of B are cut out of circuit. It will be seen that the bottom coils from which the regulating leads are brought out, are the coils which are subjected to the minimum potential in operation, so that the weakening of the insulation of these coils, by 65 bringing out the regulating leads, is of small importance.

In order to simplify the drawings I have shown the regulating leads connected directly together at the bottom of the core, but 70 it will be, of course, understood that this particular arrangement would be employed only when it is desired to adjust the number of turns of the windings initially, and to maintain the ratio of transformation constant 75 during operation. If it is desired to vary the number of turns of the winding during operation, the regulating leads could be extended to any suitable form of regulating switch, arranged outside the transformer 80 casing in the usual manner.

What I claim as new and desire to secure by Letters Patent of the United States, is,—

1. A transformer having a winding provided with regulating leads near its center, 85 whereby a central portion of the winding may be cut out of circuit.

2. A transformer winding provided with means for cutting out of circuit a portion of the turns near the center of the winding. 90

3. A transformer having a winding comprising a plurality of independent coils connected in series, the central coil or coils being provided with regulating leads whereby a portion of said central coils may be cut out of 95 circuit.

4. In a transformer, a rectangular core, two sets of coils on opposite sides of said

core, each set comprising a plurality of coils arranged side by side and connected in series and the end coil of one set being connected to the end coil of the other set to place the two sets in series, and regulating leads connected to intermediate points on the end coils which are connected to each other.

In witness whereof, I have hereunto set my hand this 7th day of September, 1906.

JOHN J. FRANK.
